UNITED STATES PATENT OFFICE

ROLAND FARLEY, OF NEW YORK, N. Y.

WINDOW LOCK

Application filed June 30, 1930. Serial No. 465,033.

This invention relates more especially to window locks for positively securing window sashes in any positions to which they may be adjusted or for interlocking two window sashes in any relative positions to which they may be adjusted.

The primary object of my invention is to provide an improved construction, combination and arrangement of parts in a device of this character whereby the window sashes may be adjusted one at a time to any desired position and interlocked in their relative adjusted positions by means of a latch or lock which may be simply and economically constructed and adapted to be applied as an attachment to windows of well-known construction.

One of the objects of my invention is to provide a window lock attachment of improved form and construction which can be readily applied to windows already in use without any considerable alteration or labor being required for placing the device in service.

More particular objects of invention will be understood from the specification, particular features of construction being recited in the claims in connection with the attached drawings which show an adaptation of my invention to a two-sash window construction such as those commonly provided in houses, office buildings, etc.

In the drawings,

Figure 1 is a front elevation of a two-sash window provided with my improved locking device;

Figure 2 is an enlarged horizontal section taken on the line 2—2 of Figure 1, parts being shown in plan;

Figure 3 is a vertical section taken on the line 3—3 of Figure 2, parts being shown in elevation;

Figure 4 is a vertical section corresponding to the line 4—4 of Figure 3, parts being shown in elevation;

Figure 5 is a fragmentary vertical section on the line 5—5 of Figure 2, parts being broken away and parts shown in elevation; and

Figure 6 is a fragmentary section on the line 6—6 of Figure 2.

According to the embodiment of my invention shown in the drawings, a window frame 1 of usual construction is provided with a side board 2. Mounted within the window frame 1 are upper and lower window sashes 3 and 4, said window sashes having their side edges in slidable engagement with the side board 2 of the window frame. An outer guide strip 5 and an inner molding strip 6 serve to guide the sashes 3 and 4 in their upward and downward movements. According to the drawings, my invention is shown as an attachment for the windows in office buildings, dwellings, etc. For this purpose, a suitable housing 7 which may be of rectangular form as shown in Figure 4, may be set into an opening formed in the side board 2 of the window frame and provided with flanges 8 which as shown in Figure 5 may be inset so as to bring the outer surface 70 of the housing 7 flush with the guiding surface of side board 2. A locking bar 9 which is preferably arranged within the upper forward corner of the housing 7 as indicated in Figure 3, is normally retained in position 75 against the front wall of the housing by means of a leaf-spring 10 which may be riveted at 11 to the inner wall of said housing. As shown in Figure 2, the locking bar 9 carries two locking pins or bolts 12 and 13 which are of unequal length and project through suitable openings in the front wall of the housing. These locking pins or bolts may be adapted to interlock with the slidable edges of the sashes 3 and 4 by providing a series of sockets 14 and 15 in the edges of said window sashes for the reception of said locking pins. A push rod 15' which is preferably made rectangular in cross-section and integrally joined to the lock-bar 9, is reciprocably mounted in the front and back plates of housing 7. Said push rod may be provided with a finger grip 16 at its outer end which is preferably arranged to project in front of the upper rail of the lower sash 4. 95 Mounted within the molding strip 6 is a socket 17 for the push-rod 15', said socket being provided with an escutcheon plate 18 which may be secured to the molding strip 6 by rivets 19. As shown best in Figure 5, 100

the push-rod 15' is provided near its outer end with a series of axially-spaced notches 20. Movable about a pin 21 below the push-rod 15' is a latch plate 22 which is adapted to engage in one or another of the notches 20 for the purpose of retaining said push-rod in different adjusted positions. Said latch is held in locking position by means of the pressure exerted by leaf-spring 10 upon the lock-bar 9 and transmitted by said lock-bar by means of push-rod 15'. Suitable means for reenforcing the latch plate 22 under this pressure, may be provided by a flanged support or post 23 which is adapted to engage the outer edge of said latch plate in locking position. By an inspection of Figure 2, it will be understood that when the window lock occupies a position in which the locking pins 12 and 13 project into the sockets 14 and 15, the latch plate 22 may be introduced into the innermost notch 20 to provide a safety catch for preventing a surreptitious entry. By moving the push-rod 15' inwardly and permitting the latch plate 22 to occupy the intermediate notch 20, the locking pin 12 is latched in retracted position and the lower sash 4 is thus left free to be raised or lowered at will. Whenever the latch plate 22 is in engagement with the outermost notch 20, both locking pins 12 and 13 will be latched in release position so that both upper and lower sashes may be moved at will. As shown in Figures 2 and 3, an auxiliary leaf-spring 23' may be riveted at 24 to the back wall of the housing 7 and thus arranged to apply additional pressure to the lock-bar 9 upon the completion of its initial movement under the resistance of leaf-spring 10 during the retraction of locking pin 12 from its socket 14. The release of the lower sash may be accomplished under a lighter pressure than that applied to the push-rod 15' for releasing the upper sash 3. This difference in pressures applied to the push-rod 15' provides simple and effective means for preventing the accidental release of the upper sash when the intention is to release only the lower sash. For convenience in adjusting the position of the upper sash 3, the lower sash 4 may be dropped to its lowermost position and permitted to rest there until the upper sash is properly positioned after which a movement of the lock-bar or push-rod to middle position permits the desired adjustment of the lower sash.

I claim:—

1. In a window lock, the combination of a bar adapted to be arranged within a side rail of a window frame and transversely with respect to the slidable edges of two adjacent window sashes, said locking bar being provided with locking pins of different lengths adapted to interlock respectively with said window sashes, and a push-rod carried by said

locking bar and presented from said guide rail of the window frame.

2. In a device of the character described, the combination with a window frame provided with oppositely-arranged uprights, of relatively movable sashes having their lateral edges slidably engaging said oppositely-arranged uprights, a locking bar movable breadthwise in one of said uprights and in a plane transverse to the adjacent lateral edges of said relatively movable sashes, said locking bar being provided with locking pins of unequal lengths adapted to interlock with said sashes respectively and with a push-rod movable endwise in front of said window sashes, a primary pressure means operating continuously on said locking bar for resisting its displacement in a direction away from said edges of the window sashes, and a secondary pressure means arranged to operate upon said locking bar after the shorter locking pin has been retracted from its particular window sash.

ROLAND FARLEY.
